(57) **CLAIM**

The ornamental design for an earphone, as shown and described.

DESCRIPTION

FIG. 1 is a front view of an earphone showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof; and,

FIG. 8 is an enlarged view of a portion indicated by lines 8-8 in FIG. 1.

The broken lines in the drawings depict portions of the earphone that form no part of the claimed design.

1 Claim, 7 Drawing Sheets
